Primary Examiner — Garth Rademaker*Assistant Examiner* — Melanie Pellegrini(74) *Attorney, Agent, or Firm* — James Creighton Wray(57) **CLAIM**

The design for a badge or pin, as shown and described.

DESCRIPTION

FIG. 1 is a top perspective view of the badge or pin.

FIG. 2 is a bottom perspective view of the badge or pin shown in FIG. 1.

FIG. 3 is a top view of the badge or pin.

FIG. 4 is a front view of the badge or pin, the rear view is a mirror image thereof.

FIG. 5 is a bottom view of the badge or pin.

FIG. 6 is a right side view of the badge or pin; and,

FIG. 7 is a left side view of the badge or pin.

The back view of the badge or pin is substantially identical to the front view shown in FIG. 4.

1 Claim, 4 Drawing Sheets(56)
